FIG. 1.

FIG. 2.

INVENTOR

W. Soukup,

By
Watson, Corl. Mowr. Grindle
AMVS

UNITED STATES PATENT OFFICE.

WENZL SOUKUP, OF KARLSBAD, CZECHOSLOVAKIA.

EGGBEATER.

Application filed January 22, 1923. Serial No. 614,310.

To all whom it may concern:

Be it known that I, WENZL SOUKUP, a citizen of the Republic of Czechoslovakia, residing at Karlsbad, in the Republic of Czechoslovakia, have invented certain new and useful Improvements in Eggbeaters; and I do hereby declare the following to be a full, clear, and exact description of the invention, such as will enable others skilled in the art to which it appertains to make and use the same.

My invention relates to improvements in egg beaters and the like, such as are used for beating eggs, whipping cream, mixing dough and accomplishing similar results, and the object of the improvements is to provide a power operated apparatus which can easily be manipulated. With this object in view my invention consists in providing an implement of the type referred to which consists of a frame adapted to be held by the hand of the operator and carrying the beating members and a motor such as an electromotor for operating the beating members.

For the purpose of explaining the invention an example embodying the same has been shown in the accompanying drawing in which the same reference characters have been used in all the views to indicate corresponding parts. In said drawing,

Fig. 1, is an elevation of the beater with the wall of the frame partly broken away, and

Fig. 2, is an elevation of the beater looking from the left in Fig. 1.

In the example shown in the figures the beater consists of a U-shaped frame 12 having a plate 19 secured thereto, said parts providing a casing enclosing the operative parts of the beater. To the web portion of the frame 12 a handle 11 is secured. In the lower flange portion of the frame two sleeves 5 and 6 are rotatably mounted, and to the said sleeves rods 1 and 2 are secured by means of screws 7 and 8, which rods are made integral with rings 3 and 4 providing the beating members. To the upper end of the sleeve 5 a spindle 9 is secured which is rotatably mounted in the upper

flange of the frame 12. To the sleeve 6 a spindle 10 is secured which is rotatable in a bracket 13 mounted on the lower flange of the frame 12.

To the rotary sleeves 5 and 6 meshing gear wheels 14 and 15 are secured, and the shaft 9 carries a gear wheel 16 which is in mesh with a pinion 18 secured to the shaft of an electromotor 17 mounted within the said frame and on the lower flange thereof.

Electric energy is supplied to the motor by means of a cable 20 connected with terminals 21 and passed through a bore of the handle 11. On the handle there is a hand operated switch 22.

The operation of the beater will be readily understood. The cable is connected to a source of electric energy, and the operator holds the beater by the handle. When depressing the switch 22 current is supplied to the electromotor 17, which transmits rotary movement to the beating members 3 and 4 through the intermediary of the gear wheels 18, 16 and 14, 15. By unscrewing the screws 7 and 8 the beating members can be readily removed for cleaning the same or putting in beating members suitable for a different kind of work.

While in describing the invention reference has been made to a particular example embodying the same I wish it to be understood that my invention is not limited to the construction shown in the drawing, and that various changes may be made in the general arrangement of the apparatus and the construction of its parts without departing from the invention.

I claim:

1. In apparatus of the class described in combination, a frame, a pair of parallel shafts rotatably mounted therein, means on each shaft for removably attaching and wholly supporting a beater element, a driving connection between the shafts, an electric motor in the frame, a driving connection between the motor and one of the shafts, a handle secured to the frame, and a single housing enclosing the motor and drive mechanism.

2. In a power driven egg beater, a U-

100

shaped frame, a pair of parallel shafts journaled in the arms of said U, a motor supported by the base of said U and having a shaft parallel to said pair of shafts, a driving connection between the motor and said shafts so that they are driven in opposite directions at the same speed, and a single unitary housing interfitting with said

frame to enclose the motor and drive mechanism.

In testimony whereof I hereunto affix my signature in the presence of two witnesses.

WENZL SOUKUP.

Witnesses:

W. W. SCHOTT,
JUG. ALEXHEHEL.
